UNITED STATES PATENT OFFICE.

LESLIE W. CLAYBOURN, OF MILWAUKEE, WISCONSIN.

SHAVING MACHINE.

Application filed September 21, 1926. Serial No. 136,841.

My invention relates to shaving machines for shaving printing plates, including so-called electroplates, etchings, stereotypes, and the like.

It is the object of my invention to provide a novel arrangement of rotary cutter-head and novel shaving means acting successively on the back of the printing plate, so arranged that the rotary cutter-head reduces the printing plate to proximate thickness followed by the action of the shaving means, to produce a completely shaved printing plate at a single relative travel between the rotary cutter-head and shaving means on the one part and the printing plate on the other part; and, further, to provide hold-down means coacting with the printing plate and mounted in novel manner with relation to the rotary cutter-head and shaving means, pressing all portions of the printing surface of the printing plate against its support throughout the area of the printing surface in order to reduce the printing plate to uniform thickness throughout the area of the printing surface with the aid of the combined coaction of the rotary cutter-head and the shaving means, in order to produce a printing plate in which the necessity for make-ready for printing with an even printing pressure is reduced to the minimum.

It is the object of my invention further to provide means whereby to adjust the distance between the cutting agencies and the support for the printing plate, so that printing plates of different thicknesses may be readily produced; further, to provide means whereby to adjust the elevational relation between the rotary cutter-head and the shaving means, so as to control the thickness of the shaving taken off of the back of the printing plate by the shaving means; and, further, to provide means whereby to adjust the distance between the cutting agencies and hold-down means and the support for the printing plate without disturbing the adjusted relation between said agencies and hold-down means.

The invention will be further readily understood from the following description and claims, and from the drawings, in which latter:

Fig. 1 is a side elevation of my improved device.

Fig. 2 is a front end elevation of the same.

Fig. 3 is a rear end elevation of the same, partly broken away.

Fig. 4 is a plan view of my improved device.

Fig. 5 is a cross-section of the same, taken on the line 5—5 of Fig. 1, partly broken away.

Fig. 6 is a vertical longitudinal section, taken on the line 6—6 of Fig. 4, partly broken away, showing the means for adjusting the fixed knife and the hold-down means.

Fig. 7 is a front elevation of a detail of the hold-down means, partly broken away; and

Fig. 8 is a vertical longitudinal section, partly broken away, showing a modification of the hold-down means.

I have in the present exemplification shown the travel between the rotary cutter-head and shaving means on the one part and the support for the printing plate on the other part, accomplished by travel of said support, although it is obvious that similar results may be obtained by causing travel of the rotary cutter-head and of the shaving means with relation to a stationarily positioned printing plate, this latter arrangement being exemplified in a companion application for patent on improvements in shaving machines, filed by me September 23, 1926, as Serial No. 137,265, and copending herewith.

The frame of the machine is exemplified at 11. A carriage 12 is arranged to travel back and forth lengthwise of the frame, being guided by guideways 13 between the frame and the carriage. The carriage is provided with a supporting surface 14 and forms a table for supporting the printing plate, shown at 15.

The printing surface 16 of the printing plate is presented toward the supporting surface of the table. The supporting surface of the table is exemplified as a plane surface, although it is obvious that my invention is also applicable in machines wherein the supporting face of the table is the sector of a cylinder, as when reducing the thicknesses of curved plates.

The travel of the table is shown accomplished by providing the table with a pair of racks 21 with which pinions 22 on a cross-shaft 23 mesh. The cross-shaft is journaled in suitable bearings on the frame 11. Rotation of the shaft 23 is suitably accomplished, as by fixing a gear 24 to said shaft. A pinion

25 on a stud-shaft 26 meshes with the gear 24. A pilot-wheel 27 is fixed to the pinion 25, to manually operate the table. Power means may also be provided for causing travel of 5 said table.

A supplemental frame 28, shown as a slide, comprises sides 29 and cross-bars 30, 31 rigid therewith. The sides are guided in guideways 32 between the main frame and said 10 sides. Adjusting screws 33 are threaded in threaded lugs 34 on said respective sides, and are journaled in bearings 35 on the respective sides of the main frame. Spiral gears 36 are fixed to the lower ends of said adjusting 15 screws. The adjusting screws are held end-wise in their bearings between said spiral gears and collars 37, fixed to said adjusting screws. A cross-shaft 38 is journaled in bearings 39 in the main frame, and has spiral 20 gears 40 fixed thereto, which respectively mesh with the spiral gears 36.

A hand-wheel 41 is fixed to said cross-shaft for turning the same, and thereby adjusting the slide or supplemental frame up and down 25 on the main frame. A clamp-bolt 42 is received through a slot 43 in the slide, at each side of the machine, and is threaded into the main frame, for clamping the slide in adjusted positions.

30 A rotary cutter-head 45 is provided with axles 46, journaled in bearings 47 upon the supplemental frame. These bearings may be adjusted, as by forming the same as bearing blocks, the bearing block at each end being 35 slidable in a guideway 48 in the slide, between adjusting screws 49, 50, respectively threaded in threaded holes 51, 52, and bearing upon the bearing for adjusting the bearing and clamping the same in adjusted positions. Jam-nuts 53, 54, hold the adjusting screws in adjusted positions. The cutter-head is suitably 40 rotated, as by means of a belt received over a suitable pulley 55 fixed to one of the axles 46. The threaded hole 51 is in a strap 56 fixed to 45 the slide 28 by bolts 57.

Shaving means coat with the rotary cutter and are shown as a shaving knife 61, which may be termed a fixed knife in contradistinction to the rotary cutter-head, and 50 is fixed in position relative to the axis of rotation of the rotary cutter-head. The shaving knife is shown as an integral knife extending crosswise of the machine, but it will be readily understood that the same may be 55 made in sections.

The shaving knife includes a cutting edge 62, in rear of which there is a bearing face 63 arranged to bear upon the rear face of the printing plate. The bearing face is a 60 narrow flat face which holds all portions of the printing plate adjacent to the cutting edge downward to prevent gouging of the printing plate and smooths the rear surface of the printing plate, and polishes the same. 65 In rear of the bearing face there is a receding

face 64, which recedes away from the plane of the printing plate, for forming a clearance space 65 between the printing plate and the body of the shaving knife.

The front end of the shaving knife includes 70 a directing face 66, which aids in directing the direction in which the shavings and chips separated from the back of the printing plate by the cutting edge 62 shall curl, for ready release and discharge of said shavings and 75 chips. This directing face if extended would form a chord in the circle of the path of rotation of the cutting edges of the rotary cutter-head. Above this face there is a receding face 67, which recedes away from the circle 80 of the rotary path of the cutting edges of the rotary cutter-head, for permitting quite close approach between the shaving edge of the shaving means and the point of coaction 85 between the rotary cutter-head and the printing plate.

If it is desired to sharpen the shaving knife, the grinding preferably takes place upon the bearing face 63, whereby the cutting edge, if such grinding is to a material extent, is caused to recede slightly from the vertical plane in which the axis of rotation 90 of the rotary cutter-head is located.

Means are provided for adjusting the shaving knife, shown as comprising resistance screws 71, threaded in threaded holes 72 in the cross-piece 31, and clamp-bolts 73 threaded in threaded holes 74 in the fixed knife and extending through slots 75 in said cross-piece. Washers 76 are received between 95 the heads of said bolts and said cross-piece. The clamp-bolts may be partly relieved and the adjusting screws adjusted for causing approach or recession of the cutting edge of the fixed knife with relation to the plane of the 100 support for the printing plate, and after adjustment the clamp-bolts are drawn up for clamping the shaving knife to the cross-piece.

Backing bolts 77 may also be provided, the 110 same being threaded in threaded holes 78 in the cross-piece 31, and secured in adjusted positions by means of jam-nuts 79. These backing bolts may be adjusted during the adjustment of the shaving knife for determining the approach of the shaving knife toward the cylinder of the path of the cutting edges 115 on the rotary cutter-head.

The rotary cutter-head is shown as a cutter-head having cutter-blades 81 integral 120 therewith, although the cutter-blades may be releasable. These cutter-blades are shown of spiral form. The cutter-blades respectively have a cutting edge 82, a clearance face 83 in rear thereof, there being a guiding face 84 at the front of the cutter-blade, which may be ground for sharpening the cutter-blade, whereby the diameter of the cutter-blade is slightly reduced, which may if desired be compensated for by adjustment of the rotary 125 130

cutter-head with relation to the plane of the support for the printing plate. The guiding face also directs the chips and shavings made by the rotary cutter-head so as to clear 5 the cutter-head and be discharged from the machine.

The rotary cutter-head and the shaving means form cutting agencies for the rear face of the printing plate, for reducing the printing plate to the desired thickness. The thickness of the shaving produced by the shaving means is determined by the relative adjustment to elevation of the rotary cutter-head and the fixed knife.

15 Hold-down means are provided for the printing plate, for pressing preferably all portions of the printing surface of the printing plate toward the supporting surface, so as preferably to bring all portions of the 20 printing surface into parallelism with said supporting surface, and ironing out all unevenesses there may be in said printing surface, caused for instance by depressions, exemplified at 85 therein, so as to bring the 25 printing lines in the whole of said printing surface into parallelism with said supporting surface, so that when the cutting agencies coact with the printing plate, the body of the printing plate will be so cut as to have an even 30 thickness throughout its printing portions. For these reasons the hold-down means act in close proximity to the cutting means, and are arranged in narrow sections close to each other crosswise of the machine.

35 The hold-down means are exemplified as spring fingers 101, there being a series of these spring fingers, shown arranged crosswise of the machine, in close proximity to each other, so that all portions of the printing 40 plate may be independently acted on, while the cutters are reducing the printing plate to thickness. These spring fingers are shown as having bevels 102 at their ends adjacent to the rotary cutter-head, so that the inner end 45 portions of the spring fingers act with great pressure upon the printing plate close to the rotary cutter-head. The spring fingers have a slightly receding or curved under surface, exemplified at 103, against which the advancing edge or high portions at the rear face of 50 the printing plate act, so as to be readily received under the spring fingers.

The spring fingers are preferably adjustable, they being shown separately adjustable and collectively adjustable in the present exemplification. Thus each of the spring fingers is received in a slot 105 in a block 106, for positioning the spring finger laterally with relation to the block and preventing lateral shifting of the end of the spring finger. The 55 spring finger is clamped to the block by means of a bolt 107, received through the spring finger and threaded into the block. The block is provided with a rib 108 received in a guiding 60 groove 109 in a cross-bar 110. The block 65

is provided with a slot 111, through which a bolt 112 is received, the bolt being threaded in a threaded hole 113 in the cross-bar.

An adjusting bolt 114 is threaded in a bar 115 secured to the cross-bar, as by bolts 116, 70 and bears against the upper end of the block 106 for adjusting the latter vertically. A jam-nut 117 clamps the bolt in adjusted positions. One of these adjusting bolts and nuts is provided for each of the blocks for adjusting the 75 springs separately.

The cross-bar 110 is adjustable for adjusting the hold-down collectively. Adjusting bolts 118 are threaded in a bracket 119 on the cross-piece 30, and bear upon the cross-bar. 80 Jam-nuts 120 hold the adjusting bolts in adjusted positions. Clamp-bolts 121 are received through slots 122 in the cross-bar 110 and are threaded in the cross-piece 30 for clamping the cross-bar 110 in adjusted positions.

I have shown a modification of such hold-down means in Fig. 8, in which similar parts are designated by similar reference numerals raised to the series 200. In this exemplification a roller 225 is journaled on a pin 226 located in bearings 227 of the tines of a fork 228, formed on a bracket 229 extending from the spring finger 201, which is in turn secured to the block 206. There is a series of these 90 rollers arranged close together side by side, which act similarly to the spring fingers 101, for ironing out the printing plate and pressing all portions of the printing surface thereof toward and into parallelism with the supporting surface for the printing surface of the printing plate, so that the printing plate will be cut of even thickness throughout its 95 printing portions by the cutting means.

If it is desired to make the finished printing plates of different thicknesses it is only necessary to adjust the distance between the supporting face for the printing plate and the cutting agencies, which may be accomplished by adjustment of the cutting agencies with relation to the supporting face, or adjustment of the supporting face with relation to the cutting agencies.

I have exemplified details of the latter in my said copending application filed by me 115 September 23, 1926, Serial No. 137,265.

The former exemplification of means is illustrated in the present application, in which the space between the cutting agencies and the plate supporting surface is accomplished 120 by adjustment of the cutting agencies, which are mounted on the supplemental frame 28, the cutting agencies and the pressure agencies being simultaneously adjusted for quickly rearranging the parts for a finished printing plate of different thickness.

My improved device is simple, provides means whereby a printing plate of various thicknesses may be quickly reduced to even thickness by one passage thereof through the 130

machine, in which rotary cutting means are employed for performing the rougher cutting, and fixed shaving means are provided for doing the finer cutting, and the printing plate is ironed out, and the printing portions of its printing surface brought into the same plane for producing a printing plate which is of equal thickness throughout its printing portions in order to produce a printing plate in which the necessity for make-ready is reduced to the minimum.

Having thus fully described my invention, what I claim as new, and desire to secure by Letters Patent, is:

1. In a printing plate shaving machine, the combination of a rotary cutter-head, a shaving knife; said shaving knife having a cutting edge, a narrow bearing face in rear thereof substantially parallel with the plane of the printing plate arranged to engage the printing plate and a receding face receding adjacent to said cutting edge from the plane of the printing plate in rear of said bearing face; a support for a printing plate; said rotary cutter-head and said shaving knife operating upon the back face of the printing plate and upon the same portions in the width of the printing plate to respectively reduce the printing plate to proximate thickness and to finished thickness in one continuous operation; and means for causing travel between said rotary cutter-head and shaving knife, and said support.

2. In a printing plate shaving machine, the combination of a slide, a rotary cutter-head journaled on said slide, shaving means on said slide at one side of said rotary cutter-head, hold-down means on said slide at the other side of said rotary cutter-head, said rotary cutter-head and said shaving knife coincidentally located crosswise of the machine for both operating on the same portions of the back of the printing plate, said rotary cutter-head reducing the printing plate to approximately even thickness and said shaving knife reducing the printing plate to finished even thickness in one continuous operation, a support for a printing plate, means for adjusting said slide to elevation with relation to said support, and means for causing travel between said slide and said support.

3. In a printing plate shaving machine, the combination of a slide, a rotary cutter-head journaled on said slide, shaving means on said slide at one side of said rotary cutter-head, hold-down means on said slide at the other side of said rotary cutter-head, said rotary cutter-head and said shaving knife coincidentally located crosswise of the machine for both operating on the same portions of the back of the printing plate, said rotary cutter-head reducing the printing plate to approximately even thickness and said shaving knife reducing the printing

plate to finished even thickness in one continuous operation, a support for a printing plate, means for adjusting said slide to elevation with relation to said support, means for causing travel between said slide and said support, and adjusting means for adjusting said rotary cutter-head, said shaving means and said hold-down means independently to elevation on said slide.

4. In a printing plate shaving machine, the combination of a support for the printing plate, a shaving knife coacting with said support, a support for the shaving knife, means for causing travel between said supports, a resistance bolt adjustable between said second-named support and said shaving knife for adjusting the distance between the cutting edge of said shaving knife and said first-named support, and a clamp-bolt on said second-named support acting on said shaving knife for clamping said shaving knife to said second-named support, the axes of rotation of said bolts being substantially parallel.

5. In a printing plate shaving machine, the combination of a support for the printing plate, a shaving knife coacting with said support, a support for the shaving knife, means for causing travel between said supports, a resistance bolt adjustable between said second-named support and said shaving knife for adjusting the distance between the cutting edge of said shaving knife and said first-named support, a backing bolt adjustable between said second-named support and said shaving knife for adjusting said shaving knife in its plane, the axes of rotation of said bolts being substantially parallel, and a clamp bolt on said second-named support acting on said shaving knife for clamping said shaving knife to said second-named support.

6. In a printing plate shaving machine, the combination of a support for the printing plate, a shaving knife coacting with said support, a support for said shaving knife, means for causing travel between said supports, said shaving knife having a cutting edge extending laterally throughout a considerable portion of said supports, a series of resistance bolts adjacent said cutting edge adjustable between said second-named support and said shaving knife for adjusting the distance between said cutting edge and said first-named support, and a series of clamp-bolts laterally arranged on said second-named support acting on said shaving knife for clamping said shaving knife to said second-named support, the axes of rotation of said bolts being substantially parallel.

7. In a printing plate shaving machine, the combination of a support for the printing plate, a rotary cutter-head and a shaving knife coacting with said support, said

- rotary cutter-head and said shaving knife coincidentally located crosswise of the machine for both operating on the same portions of the back of the printing plate, said 5 rotary cutter-head reducing the printing plate to approximately even thickness and said shaving knife reducing the printing plate to finished even thickness in one continuous operation, means for causing travel 10 between said rotary cutter-head and shaving knife, and said support; means for adjusting the relative distance between said rotary cutter-head and shaving knife, and said support, said shaving knife located at one side 15 of said rotary cutter-head, sectional hold-down means at the other side of said rotary cutter-head, and means for independently and collectively adjusting said sectional hold-down means with relation to said support. 20 8. In a printing plate shaving machine, the combination of a support for the printing plate, a rotary cutter-head, shaving means at one side of said rotary cutter-head, sectional hold-down means at the other side 25 of said rotary cutter-head, said rotary cutter-head and said shaving knife coincidentally located crosswise of the machine for both operating on the same portions of the back of the printing plate, said rotary cutter-head reducing the printing plate to approximately even thickness and said shaving knife reducing the printing plate to finished even thickness in one continuous operation, means independently adjusting the sections 30 of said hold-down means, a support for the latter, means for adjusting said last-named support whereby to collectively adjust said sections of said hold-down means, and means for causing travel between said supports. 35 9. In a printing plate shaving machine, the combination of a frame, a support there-in for a printing plate, a slide, means for adjusting said slide on said frame, a rotary cutter-head on said slide, shaving means on 40 said slide at one side of said rotary cutter-head, sectional hold-down means on said slide at the other side of said rotary cutter-head, said rotary cutter-head and said shaving knife coincidentally located crosswise of the machine for both operating on the same portions of the back of the printing plate, said rotary cutter-head reducing the printing plate to approximately even thickness and said shaving knife reducing the printing plate to finished even thickness in one continuous operation, means for adjusting the distance relation between said support and said aforementioned means on said slide, means for independently adjusting said aforementioned means on said slide with relation to said support, and means for causing travel between said support and said slide. 55 10. In a printing plate shaving machine, the combination of a frame, a support there-in for a printing plate, a slide, means for adjusting said slide on said frame, a rotary cutter-head on said slide, a shaving means on said slide at one side of said rotary cutter-head, sectional hold-down means on said slide at the other side of said rotary cutter-head, said rotary cutter-head and said shaving knife coincidentally located crosswise of the machine for both operating on the same portions of the back of the printing plate, 60 said rotary cutter-head reducing the printing plate to approximately even thickness and said shaving knife reducing the printing plate to finished even thickness in one continuous operation, means for adjusting said slide with relation to said support, means for independently adjusting the sections of said hold-down means with relation to said support, means collectively adjusting said sections of said hold-down means with relation to said support, and means for causing travel between said support and said slide. 65 70 75 80 85

In testimony whereof, I have hereunto signed my name.

LESLIE W. CLAYBOURN.
